UNITED STATES PATENT OFFICE.

DAVID B. BROWN, OF BELLINGHAM, WASHINGTON.

SAFETY-RAZOR-BLADE RESHARPENER.

Application filed October 5, 1921. Serial No. 505,555.

To all whom it may concern:

Be it known that I, DAVID B. BROWN, a citizen of the United States, and resident of Bellingham, in the county of Whatcom and 5 State of Washington, have invented a new and useful Safety-Razor-Blade Resharpenener, of which the following is a specification.

My invention relates to improvements in safety-razor blade resharpeners, and the 10 object of my improvement is to provide a simple machine wherein a plurality of used blades of safety razors may be simultaneously placed and automatically honed and stropped on flat surfaces.

15 I attain this object with the mechanism illustrated in the accompanying sheet of drawings in which Figure 1 is an end elevation of my resharpening machine, Fig. 2 is a front elevation of Fig. 1, Fig. 3 is a plan 20 view of the blade holder, drawn on a larger scale, Fig. 4 is a side elevation of Fig. 3 and Fig. 5 is a front elevation of the lower part of Fig. 4.

Similar characters refer to similar parts 25 throughout. Certain parts are broken away to show other parts hidden thereby.

More particularly: The several elements of the frame are marked 6. A shaft 7 is mounted for revolution in bearings on the 30 top members of the frame. On shaft 7 is mounted fixed six strop disks 9 and four hone disks 12, each having a hub 10. On the facing sides of discs 9 are the leather discs 11 for stropping. Two plates 13 are ful- 35 crumed together by bolts and springs 14. Figs. 3 and 4, and forced apart at one end by spring 15. On the other end of one of plates 13 are two short studs a^{13} which register with two holes b^{13} in the other plate. A safety razor blade A is placed 40 between these ends of plates 13 with studs a^{13} in the holes in said blade by first compressing spring 15. When thus installed the pressure of said spring will firmly clamp 45 said blade. A clamp stem 16 has a cross head 17 mounted in two blocks 19 fastened to one of plates 13. Said stem extends 50 equally on both sides of the clamp on either side of which it has the cross pins 20, 20. One end of stem 16 is mounted in a longitudinal hole in oscillatable handle 21 having 55 head 22, in which is pin slot 23 and on the lower end of which is spring blade 24. Each of nine similar handles is mounted in one of a row of holes in the inner end of one of 55 nine bars fastened to bar 26 fixed on the

brackets of bearings 8 to lie in front of said stropping and honing disks, said holes being placed to locate each handle on a medial line between two of said discs. Shifting bar 27 60 is mounted for longitudinal oscillations in slideways in the front ends of upper parallel bars 32, 32, and for transverse, or up and down, movements said bars 32, 32 are each pivotally connected to one of lower parallel bars 33, 33 by one of vertical, cam-wheel yokes 34, 34. Said yokes each mounts a wheel 35 on its lower end which bears on one of two cams 36, 36. Each of said cams is mounted fixed on the outer end of shaft 70 65 37 which is mounted for revolution in bearings on frame 6. A hand stop-lever b^{37} is pivotally mounted on a front leg of frame 6 and has a notch in one end engageable with pin a^{37} in one of cams 36. When in its full-line position stop lever b^{37} prevents the revolution of shaft 37 but when in its dotted-line position it does not effect said shaft movement. A pulley 38 is mounted fixed on shaft 37 in belting relation to pulley 43 on 75 70 shaft 44. A belt 39 is mounted on said pulleys 38 and 43. Tightener pulley 40 is mounted for revolution in bearings on the free ends of links 41, 41, the other ends of which are mounted on rod a^{41} fixed to frame 80 85 6 parallel with shaft 37. A weight 42 is fixed to links 41 to force pulley 40 downward. Said shaft 44 is mounted for revolution in bearings on frame 6 parallel with shaft 37 and mounts fixed pulleys 43 and 45. Pulley 45 is in belting relation with one of disk hubs 10 which is mounted fixed on shaft 7. Belt 46 is used to connect said disk hub with pulley 45. A cam wheel 47 having cam groove 48 is mounted fixed on shaft 37. The lower end of a shifting lever 49 is ful- 90 95 crumed to a lower member of frame 6 and mounts wheel 50 engaged in cam slot 48. In the upper end of lever 49 is fixed pin 51 en- gaged in the slotted lower ends of a vertical 100 yoke bracket 30 pendent from shifting bar 27.

An electric motor 52 is mounted fixed on a lower frame member and on its shaft is fixed a pulley 53 in belting relation with 105 a pulley 55 mounted fixed on one end of disk shaft 7. A belt 54 connects pulleys 53 and 55. In each of nine holes in bar 27 is a thimble 28, which mounts a vertical staple 29 oscillatable therein. Said staple 110 engages one of springs 24 fixed in the lower end of one of handles 21.

In operation: A device for controlling an electric current, not shown, serving motor 52 is used to start and stop the power for operating the machine at will. Said motor 5 causes the revolution of shaft 7 through belt 54, shaft 44 through belt 46 and shaft 37 through belt 39. Shaft 7 can be operated while shaft 37 is held from turning by the engagement of lever b^{37} with pin a^{37} , since, 10 although shaft 44 is revolving, belt 39 is permitted to slip on pulley 38 by the yielding of belt tightener 40. Shifting bar 27 receives its up and down motion from cams 36 operating through parallel bars 32, and 15 its longitudinal movements from cam 47 operating through lever 49. Hence bar 27 may remain at rest while the stropping and honing disks are revolving. This permits cleaning said leather discs 11 and hone disks 12 and the spreading of abrasive material thereon while said bar is at rest. Blades A are clamped between plates 13 and the holders mounted in handles 21 as shown. Said holders are reversible in said 20 handles. As bar 27 moves forth and back longitudinally the outer ends of spring blades 24 are carried with it causing handles 21 to oscillate which causes blades A in their holders to be pressed first against one 25 of the revolving disks and then against the other between which they stand. The pressure of this contact between razor blades and honing and stropping disks is made yielding by spring blades 24. Also as bar 30 27 is moved up and down by cams 36 handles 21 are caused to similarly move by spring blades 24 thus causing blades A to move up and down while in contact with the honing and stropping disks. Thus both 35 40 sides of razor blades A are alternately moved up and down over flat abrasive surfaces moving rapidly beneath.

Having thus disclosed my invention, what

I claim is new and desire to secure by Letters Patent is,—

In combination, an abrasive-disk shaft mounted for revolution, a plurality of abrasive disks mounted fixed at spaced distances on said shaft, a countershaft mounted for revolution parallel with said disk shaft, power connections between said disk shaft and said countershaft, a cam shaft mounted for revolution parallel with said disk shaft, a bar mounted for transverse oscillations and longitudinal reciprocation parallel with said disk shaft, controllable frictional power connections between said countershaft and said cam shaft, one of a pair of cam disks mounted fixed on each end of said cam shaft, connections between each of said cam disks and said bar whereby said bar is caused to oscillate as said cam disks are revolved, a cam wheel mounted fixed on said cam shaft, power connections between said cam wheel and said bar whereby said bar is caused to reciprocate as said cam wheel revolves, a plurality of blade holders each mountable for oscillation with a holder handle about an axis parallel with the jaws of said holder, a plurality of blade-holder handles each mounted for oscillation on said axis between each two facing abrasive disks and also mounted for longitudinal reciprocation whereby said oscillations will cause a blade held in said holder to first bear against one 75 of said facing abrasive disks and then against the other facing disk and said reciprocation of said holder will cause said blade to move longitudinally while bearing on said disks, resilient power connections between said movable bar and said handle whereby said handle is caused to oscillate on its axis when said bar reciprocates longitudinally and power means to revolve said abrasive disk shaft.

DAVID B. BROWN.
